UNITED STATES PATENT OFFICE.

EDMUND A. SCHADE, OF NEW BRITAIN, CONNECTICUT, ASSIGNOR TO THE STANLEY RULE AND LEVEL COMPANY, OF SAME PLACE.

DESIGN FOR A FRAME FOR CIRCULAR PLANES.

SPECIFICATION forming part of Design No. 22,208, dated February 7, 1893.

Application filed January 5, 1893. Serial No. 457,388. Term of patent 14 years.

To all whom it may concern:

Be it known that I, EDMUND A. SCHADE, a citizen of the United States, residing at New Britain, in the county of Hartford and State 5 of Connecticut, have invented and produced a new and original Design for a Frame for Circular Planes, of which the following is a specification, reference being had to the accompanying drawing, forming part thereof, in which the only figure is a perspective view of a frame for circular planes showing my design. *a a* designate the side bars, *b b* the ends, and *o* the cross bar, the same forming the frame for a part of a circular plane. The side 15 bars *a a* have a plane outer surface and terminate in curved ends near the ends *b b* of the frame. The ends *b b* are in the form of

a segment of a sphere with a circular elevation thereon facing obliquely upward and outward. At the rear end, I form an upwardly 20 projecting lug *d* which is rounded on its rear surface as shown. On the top of the cross bar *o* there is a boss *f* in front of which is a smaller boss *g*. The top of the boss *f* on the cross bar *o* is provided with a rabbeted recess *h* which 25 surrounds a central opening *k* through the cross bar.

What I claim is,

The design for the frame of a circular plane herein shown and described.

EDMUND A. SCHADE.
